N. Y., a corporation of New York

Application December 3, 1949, Serial No. 130,884

27 Claims. (Cl. 153—59)

1

This application is a continuation in part of applicant's application Serial No. 44,368, filed August 14, 1948, which application is now abandoned. The present invention relates to apparatus for and method of curling longitudinal edges of strips of deformable strip material; and, more particularly, to embodiments of such apparatus adapted automatically in a progressive manner with continuous draft of such strips through the apparatus to form one or more turns, or desired fractions thereof, in or roll up either or both edges toward the strip center, and the unique method of doing so as may be practiced by operations of various embodiments of the apparatus.

Prior to the present invention many different types of devices have been designed and employed to form one or more turns, or even less than a full turn, about a longitudinal axis, in elongated strips of sheet material, such as metal, e. g., lead, brass, copper, metal alloys, etc. Male and female die rollers, drawing dies with central mandrels and other means feature such devices adapted for forming hollow pipe. However, with cooperating male and female dies longitudinal curling therewith is limited to about a hundred and eighty degree (180°) turn after which a three hundred and sixty degree (360°) turn may be formed by drawing through a circular die without the use of a central mandrel if the longitudinal edges are abutted during drawing. If more than one turn is to be formed at least the last of a series of drawing dies must be equipped with a central mandrel which in turn limits the length of the product which can be formed in one operation. Such operations are entirely unsuited to formation in such strip material of one or more rolls each of a plurality of turns where no appreciable space is to be left centrally of such roll, and particularly where such strip is to be faced with a fluid or plastic coating intended to be entrapped and retained interiorly in certain minimum quantity per unit length, as in the production of fluxed solder rod disclosed and claimed in the pending application of Crowell and Philippi, Serial No. 20,294, filed April 10, 1948, now Patent No. 2,565,477, granted August 28, 1951. The fluidity or plastic nature of flux material makes it incapable of transmitting or resisting any pressure until wholly confined and thus most prior art curling procedures unfortunately result in excessive squeeze-out with production of an inferior or unsuitable product.

A general object of the present invention is to provide mechanism which is readily and eco-

2

nomically manufactured and easily and simply operated efficiently to form automatically at relatively great speed one or two longitudinally-extending rolls of one or more turns, or any desired fractions thereof, in continuous strips of deformable sheet material of the types previously indicated, such as lead, brass, copper, steel, alloys thereof and other metal alloys or metallic materials, as well as non-metallic materials having the desired characteristics adapting them to such curling operations, to form various types of products from curled strips of the selected starting sheet materials, for example, hollow pipe or tubing, tubular welding rod stock having an internal core of powdered metal or suitable flux material, coaxial cable, strands or flux-cored solder, etc., while avoiding the difficulties indicated above; and a unique method of making such products or curling the edges of strips of selected deformable material in the production thereof featured by movement of an edge of the strip while tensed into fixed-position curling means with backing of the strip thereat by convex bed means effectively to keep the strip snugged to the latter.

A more specific object of the present invention is to provide such apparatus which in curling up an edge of such strip material takes simple advantage of even a relatively low degree of rigidity transversely to transmit minor compressive forces to hold the strip along a certain path of advance while pushing die means curls up one edge thereof, unique bowing means being provided to cause the travelling strip to stay against a supporting bed during curling operations without buckling or backing away from the die means while making unnecessary use of any engaging hold-down devices which cannot be employed if the strip top surface be coated with fluid material.

Another object of the present invention is to provide supporting bed means in such apparatus which may travel with the drafted strip to eliminate frictional difficulties; and which, preferably, centrally distorts the strip temporarily during curling to assure in the curling of both longitudinal edges the formation of uniform or symmetrical rolls.

A further object of the present invention is to provide a unique method of curling or rolling up at least one longitudinal edge of a strip of deformable sheet material in an unusually simple but efficient manner by moving the strip longitudinally across convex backing means and while doing so applying lateral pressure or push and

lift to that edge progressively to roll it up while lateral strip shift is being restrained, the traveling strip being maintained under tension in the portions having their edges curled, with the tension being of such degree that the components of the resulting force applied to the strip in the direction toward the backing means is greater than components of force in the opposite direction applied to the strip as lift by the rolling operation effectively to keep the strip snugly against the backing means.

Other objects of the invention will in part be obvious and will in part appear hereinafter.

The invention accordingly comprises the features of construction, combination of elements and arrangement of parts, which will be exemplified in the construction hereinafter set forth, and the scope of the invention will be indicated in the claims.

For a fuller understanding of the nature and objects of the invention, reference should be had to the following detailed description taken in connection with the accompanying drawings, in which:

Fig. 1 is an end elevational view, with parts broken away, of an embodiment of the apparatus of the present invention;

Fig. 2 is a side elevational view, with parts broken away and in section, of the embodiment shown in Fig. 1;

Fig. 3 is an enlarged sectional detail, taken substantially on line 3-3 of Fig. 2, with parts broken away, of one of the curling die means and associated strip-supporting bed of the apparatus shown in Figs. 1 and 2, indicating relative cooperation thereof in curling an edge of a strip of sheet material;

Fig. 4 is an enlarged developed plan view taken on line 4-4 of Fig. 2 indicating progressive curling performed by the plurality of die means thereof;

Figs. 5, 6, 7, 8 and 9 are respectively enlarged cross-sectional views of the progressively curled strip produced by operation of the apparatus shown in Figs. 1 to 4 inclusive, taken substantially on lines 5-5, 6-6, 7-7, 8-8 and 9-9 of Fig. 4;

Fig. 10 is a transverse sectional view of a finished fluxed solder rod or like product resulting from a final drawing through an apertured die of the rolled strip shown in Fig. 9;

Fig. 11 is a view similar to Fig. 5, with parts broken away, showing a modified form of curling of a strip by operation of another embodiment of the apparatus of the present invention incorporating features disclosed in Fig. 14;

Fig. 12 is a view similar to Fig. 9 of the strip shown in Fig. 11 after being subjected to the final curling operation;

Fig. 13 is a view similar to Fig. 10 showing the double rolled strip of Fig. 12 after it has been drawn through an apertured die to produce a finished commercial product;

Fig. 14 is an enlarged elevational view, with parts broken away, similar to Fig. 3 but indicating variations in the structure thereof for the purpose of producing the product of Figs. 11, 12 and 13; and

Figs. 15, 16 and 17 are views similar to Figs. 5, 6 and 9 respectively, showing a modified form of the product producible with the employment of two juxtaposed strips.

Referring to the drawings in which like numerals identify similar parts throughout, embodiments of the apparatus have been illustrated in

connection with the production of fluxed solder rod products to the production of which it may be particularly adapted. However, it will be understood that the use and operation of the apparatus of the present invention and various embodiments thereof is in no way limited to the manufacture of that particular type of product, and may be employed to advantage in curling edges of strip material to form a variety of types of products such as seamed pipe, laminated tubing, rolled beading, etc. It will be seen from the drawings, and more particularly with reference to Figs. 1 to 4 inclusive, that an embodiment of the present invention may comprise suitable supporting frame structure 20. Frame structure 20 includes a cross beam or angle 21 and an inverted U-shaped bracket 22, laterally spaced apart as shown in Fig. 1 and respectively supporting journal boxes 23 and 24. The ends of a shaft 25 are rotatably supported by journal boxes 23 and 24, and hub 26 of a relatively large wheel 27 is fixed on the shaft. As best shown in Figs. 1 and 2, peripherally of the wheel 27 is provided a relatively wide flat rim 28 forming an endless rotatable band to serve as a bowed or longitudinally arched supporting bed. The rim 28 on one side is equipped with an outwardly-extending radial flange 29 to serve as an abutment, as will be more fully explained hereinafter.

The frame structure 20 is also provided at the top thereof with a cross plate 30 which supports a plurality of similar angle brackets 31, 32, 33, 34 and 35 arranged at successive stations of an arcuate path along the top portion of the wheel 27, as best shown in Fig. 2. Each of brackets 31 to 35, inclusive, has bolted thereto a laterally-extending supporting plate 36 which, as will be seen more clearly from Figs. 1 and 3, supports a bracket 37. The latter has a radially projecting portion 38 serving with plate 36 to support vertically spaced-apart bearings 39 and 40 which may be of the thrust type if desired and as shown. A shaft 41 is rotatably mounted through bearings 39 and 40 and carries fixed on its lower end a die roller 42, or other similar die wheel at another station, as hereinafter more fully explained. Of course, bearings 39 and 40 may be of the simple plain type with suitable biasing spring means to urge the die rollers toward the bed surface or wheel rim 28. As will be more readily noted from Fig. 3, die wheel 42 is of the familiar type, having therein a circumferential groove or curved surface 43, with an element of the curved surface thereof located on an arc having a radius substantially equal to the radius of curvature desired in the first formed turn of the curling. It will also be noted from Fig. 3 that the bottom end 44 of die roller 42 is juxtaposed to the outer surface of bed rim 28, but since, as is indicated, the axis 45 thereof is substantially normal to an element of the bed surface, it will be understood that at least slight clearance is preferred. However, if the axis 45 be moved to the position indicated with a dash-dot line at 46, it will be understood that the peripheral edge of the bottom end 44 of die roller 42 may be brought on the inner side to contact with the bed surface of rim 28, so that as the latter is rotated forward the die roller will be rotated therewith by contact to reduce friction between surfaces of the die roller and of the strip being curled. For this reason, die rollers are preferred, but it will readily be recognized by those skilled in the art that fixed shoes may be used in lieu thereof in cases where friction

between shoe surfaces and the drafted strip is of no serious moment.

The second, third, fourth and fifth brackets, 32, 33, 34 and 35 respectively support in like manner similar female die rollers 47, 48, 49 and 50, with each having an increasingly larger concave die groove therein to form the successive turns in the roll being curled in the edge of the strip with gradual increase in diameter of the roll as is understood in the art. Such grooves are respectively identified by numerals 51, 52, 53 and 54 and the progressive increase in the diameters of the generating arcs thereof is most readily seen from Fig. 4. Preferably, as indicated in Figs. 1 and 4, each roller supporting plate 36 is mounted to its supporting angle bracket by means of a bolt 55 extending through an elongated slot 56 in the plate, with a tightening nut 57 on the bolt permitting, when loosened, longitudinal adjustment of each plate. Thus, the die rollers carried by adjustable supporting plates 36—36 may be accurately adjusted to their desired positions progressively nearer the wheel abutment flange 29, as is clearly shown in Fig. 4.

It will be noted from Fig. 2 that the frame structure 20 is equipped with a bracket 58 which supports on the take-off side of bed wheel 27 a drawing die 59 through which the curled roll is to be drawn for desired shaping and/or reduction to the desired cross-sectional size or diameter; and, of course, it will be understood that a plurality of such drawing dies, successively arranged, may be employed for similar purposes. Beyond such drawing die structure, suitable draft means are to be provided, which has not been shown since various forms thereof are well known in the art. Such draft means may, as understood, take the form of a common drive take-up reel, which, when rotated, will apply the necessary draft to the continuous finished product.

Preferably, on the approach side of the bed wheel 27 is rotatably mounted in any suitable manner a guide roller 60 beneath which the strip is located to be fed to the wheel rim 28 at a desired point. There is also preferably provided on the approach side of the bed wheel 27 a slap shoe 61 mounted in any suitable manner so as to snug the strip to the bed surface of the wheel at the desired point. When the apparatus is to be employed for the production of fluxed solder rod, or the like, a suitable fluid applicator 62 is provided between the first die roller 42 and the slap shoe 61. For this purpose, a bracket 63 mounted on frame structure 20 may support a well 64 having a transfer roller 65 rotatably mounted therein for partial submergence in a body 66 of liquid or plastic flux material. A rotatably-supported applicator roller 67 transfers flux material from the surface of transfer roll 65 to the outer face of the strip as it is moved in contact therebeneath.

In operation of the embodiment of the invention shown in Figs. 1 to 4 inclusive, when employed for the purpose of producing fluxed solder rod, a suitable strip 68 of deformable and settable sheet solder material which, of course, has some or certain limited rigidity so that it will transmit transversely minor compressive forces there-across or some push applied laterally to edges thereof, is supplied from any suitable source such as a braked supply reel (not shown). The strip is brought forward, lapped beneath and beyond guide roller 60, and then up over the top portion of bed wheel 27 with slap shoe 61 snug-ging it to the outer surface of wheel rim 28 at 75

take-on station 69, and then successively beneath flux-applying applicator roller 67 at the applicator 62 and past the various curling stations at die rollers 42, 47, 48, 49 and 50, to be drafted off as a rolled product and drawn through shaping die 59 by the driven draft take-up reel. The strip-supporting portion of the rim 28 of fixed-position bed wheel 27 constitutes longitudinally-arched, strip-backing or bed means arranged longitudinally in arcuate outline as viewed from the side as distinguished from any transverse or cross-sectional shaping thereof; and thus defines a fixed route, longitudinally-arched, curved path along which the strip is dragged during the curling of its edges. Such longitudinally-arched bed means is not transported in any direction from its original fixed position during the curling operation, even though by wheel rotation successive arcuate portions of the rim progressively constitute the fixed-position, longitudinally-arched bed means as the curling operation progresses. As will be seen from Fig. 4, the flux-surfaced strip 68 has one edge 70 thereof abutted or snugged against the inner face of abutment flange 29 and the inner side of the first die roller is arranged in the path of the opposite edge 71 of the strip so that as the latter is drawn past it, the concave groove 43 therein may cause edge 71 to be lifted away from the supporting surface of bed wheel 27 and turned or curled up approximately through one hundred and eighty degrees (180°) as indicated in Fig. 5. At the second die roller 47, the curled portion of edge 71 of the coated strip 68 may be further lifted and turned over approximately to complete a three hundred and sixty degree (360°) turn, as is indicated in Fig. 6. At the third die roller 48, the curled portion of strip edge 71 may be lifted and turned over still further through an additional one hundred and eighty degrees (180°), as is indicated in Fig. 7, with the fourth die roller 49 further possibly turning it over one hundred and eighty degrees (180°) to complete two complete turns, as shown in Fig. 8. The die roller at 50 further lifts and curls the curled edge 71 of strip 68 longitudinally to complete, if desired, two and one-half three hundred and sixty degree (360°) turns therein to produce the "jelly roll" product shown in Fig. 9. The curvature of the concave groove 43 in die roller 42, and those of the successive die rollers 47, 48, 49 and 50, is such as to assure the provision of uniform spacing between successive turns in the curled strip to accommodate the thickness of the coating 72 of flux material applied by doctor roller 67, which is most readily seen from an inspection of Figs. 6, 7, 8 and 9. Further, it is to be understood, the successive die rollers may each turn over the strip edge considerably less than one half of a complete turn, if desired, more stages being used to assure the formation of the desired number of complete turns. In such fashion the required pressure on the strip edge can be reduced with less curling being performed at each stake. The curvature of the concave groove in each die roller will govern extent of each curling operation.

The rolled product of Fig. 9 is then drawn through die 59 to draw it down and/or shape it as desired to produce, for example, a fluxed solder rod of a structure similar to that shown at 73 in Fig. 10. This drawing causes the edge 70 to be curved by deformation and pressure at 74 to the outer surface of the underlying turn, so as to seal within the flux material to avoid there-after, during any subsequent drawing down and

handling, squeeze-out of flux material which intervenes as a coating 12 the successive turns of the product. It will be readily seen that in this manner, the product roll may be rapidly formed in a continuous manner.

The outwardly bowed, longitudinally arched or convex supporting bed means which defines a longitudinally arched curved path, as provided by the upper portion of the rim 28 of bed wheel 27, and the application of some tension to the strip 68 by drag as it is drafted forward, causes that strip to be held snugly against portions of the outer side of the bed rim means at least at the curling stations and without any necessity for any hold-down mechanism. The abutment flange 29 assures that the strip will be held in its predetermined path so that it cannot move laterally back away from the die rollers as they successively push transversely against the strip, curling up the free unabutted edge. Due to the fact that the strip has some rigidity transversely, it will even when flat resist longitudinal buckling to a degree during the curling if only its far edge is snugged up against abutment means. However, excessive lateral pressure would, of course, tend to buckle such flat strip of deformable material longitudinally; i. e., push it up centrally. This is simply but uniquely avoided by drafting the strip over the outwardly bowed supporting bed provided by the bed wheel.

Of course, it will be understood that the outwardly bowed, longitudinally arched or convex bed means may be provided in the form of a fixed convex plate or in the form of an endless belt guided through and past the curling stations over suitable convex structure. In any event, a moving, relatively fixed-position, supporting bed means is preferred over a fixed supporting bed since, in apparatus featured by the former, the strip rides over the longitudinally arched supporting bed means without any sliding action and thus without any friction. Although it may be preferred that when the bed means is in the form of a bed wheel it be mounted for free rotation as hereinbefore indicated, it is to be understood that the bed wheel may be positively driven at a speed to assure a rate of linear travel of its rim at approximately the speed of forward travel of the strip, within the scope of the present invention.

Regardless of what form the bowed or longitudinally arched supporting bed means may take, the arcuate shape of the path of travel of the strip being curled thereby will adapt the apparatus to the curling operations, making the strip material follow the contours of the concave grooves in the curling die rollers without necessitating the employment of mating dies to force the strip material into the curling grooves. When one of the curling die rollers picks up or lifts away from the bed means the edge portion of the strip (in other words, pushes it out away from the bed means regardless of the orientation of the latter and of the path of travel of the strip) by engagement thereof in the roller curling groove, it stretches the metal slightly since the effective diameter of the arched or bowed portion of the strip lifted away from the bed means at that point becomes greater than the diameter of a circular arc which lies along at least a portion of the bed-defined path at that point. Consequently, the lifted portion of the strip must stretch enough to correspond to the increased circumference of this larger diameter. Obviously, the strip tends to resist this stretch, and

as a result, accurately follow the contour of the concave groove in the curling die roller, which is of extreme importance in assuring formation and maintenance of uniform spacing between successive turns in the product roll as it is curled up so as to avoid flow or excessive squeeze-out of coating or flux material.

It may be understood from the preceding description that opposite edges of such a strip may be curled or rolled up simultaneously to provide two parallel longitudinally-extending rolls in the strip. This is made quite evident from Figs. 11 to 14 inclusive, wherein in the latter is shown a modified form of bed wheel 127, preferably having a slightly different bed rim 128 over which is arranged the die rollers in opposed pairs. For example, in the form of the apparatus shown in Fig. 14, although the bed rim 128 may be developed by a straight line element extending parallel to the axis of the bed wheel 127, preferably it is dished; that is, its outer surface 75 is shaped in the form of a flat V in transverse section for a purpose to be more fully apparent in connection with the operation hereinafter described.

Each die roller supporting bracket 132 of the embodiment of Fig. 14 has, as indicated, its flanges arranged in the form of an acute angle with each supporting plate 136 also preferably bent slightly so as to tilt the axis of each die roller 147 over toward the mid plane indicated with a dotted line at 76. As a result, the bottom end 144 of each die roller 147 is lifted away from the outer surface 75 of the rim 128 except on the inner side at a point of contact at 77 nearest the mid plane 76. This permits die roller 147 to be rotated by friction wheel action with forward rotation of the bed wheel 127, thereby eliminating any possibility of sliding friction between surfaces of the strip being curled and the surface of the groove in the die roller, and also permitting the bottom end of the die roller to be brought down into contact with the bed surface without introduction of any sliding friction therebetween, while assuring that the bottom edge of the groove is as close as possible to the bed surface to avoid necessity of excessive lifting of strip material up away from the bed surface with attendant excessive stretching during the curling. It will be noted from Fig. 14 that preferably the peripheral edge of the bottom end 144 of each die roller 147 is chamfered as indicated at 78 to accomplish these ends in the most efficient manner.

It will be understood, of course, that the die roller means at the various other curling stations in the apparatus of Fig. 14 will be substantial duplicates of the pair thereof shown, except for their relatively lateral spacing accomplished by longitudinal adjustment of the supporting plates 136, 136, and, of course, with the practice of the teachings of Fig. 4 with respect to the gradually increasing size of the curling grooves in the succeeding die rollers.

In operation of apparatus which employs opposed pairs of die rollers as proposed in Fig. 14 for curling up opposite edges of a strip 68, it will be understood, of course, that one die roller serves as abutment means for the opposed die roller during curling operation by the latter, and vice versa. However, it has been found that if the supporting bed surface be flat in a transverse direction, there may be some tendency for the strip to be shifted laterally with formation of more turns in one of the two rolls than in the other. The relatively flat V-shape of the bed surface 75 prevents this.

undesired action from occurring since, in drafting the deformable strip over the arcuate V-shaped bed, the strip is temporarily deformed transversely to the shape of the bed surface, as is indicated in Fig. 14 and also in Figs. 11 and 12. This slight temporary deformation of the strip causes it to be held securely in alignment with the central plane 76 during the application of pushing forces against the opposite edges thereof as they are curled up by operation of the opposed pairs of curling rollers.

The first pair of opposed curling rollers at the first curling station of the apparatus of Fig. 14 will shape the coated strip 68 substantially in the form shown in Fig. 11. Succeeding pairs of opposed die rollers, generally of the form indicated in Fig. 14, will gradually increase the number of turns in the opposed edges of the strip 68 to form the two parallel longitudinally-extending rolls 79, 78 shown in Fig. 12. Thereafter, if such double roll production of Fig. 12 be drawn through a circular drawing die, such as that at 59 in Fig. 2, the product will be drawn substantially to the form indicated in Fig. 13; i. e., into a cylindrical rod 80, with the various layers of strip solder and intervening films or coatings of flux material substantially arranged as shown in that figure. In such a product, a secure seal is provided along the plane 81 of uncoated contacting surfaces so as to seal securely the flux material within the interior of the cylindrical rod. The resulting product has many meritorious features which are outlined in the above identified Crowell and Phillipi joint application but which need not be here recited since that product forms no part of the present invention. However, the superior merits of that product do make important the apparatus of the present invention which is so efficiently adapted to produce it in a simple, rapid and economical manner.

As should be now understood, use of embodiments of the apparatus of the present invention are not limited to operation upon single layer strips. For example, as indicated in Figs. 15, 16 and 17, a plural layer strip which may comprise a lamina 168 of solder material, a narrower lamina 268 also of solder material, an intervening layer 72 of flux material, and a topping layer 172 also of flux material, may be curled up together into a double coil, single "jelly roll" product 173, with the die roller at the first station forming the turn indicated in Fig. 15, the second die roller at the second station forming the turns indicated in Fig. 16, and the rolled product 173 shown in Fig. 17 being formed at a third station by a third die roller. Of course, it will be understood that only for purposes of clarification are the successive turns in Figs. 16 and 17 indicated as being formed around a central void of excessive volume, and, of course, it is obvious that the resulting double coiled product may be thereafter drawn down into any desired cross-sectional shape. Further, it will be understood that such plural layer strip may be used to make a product similar to that shown in Figs. 12 and 13, with opposite edges of such composite strip curled or rolled up to provide two parallel longitudinally-extending rolls as therein proposed.

Practice of the present invention is not limited to the employment of pulling means beyond the convex bed means to draft the strip thereover and drag means located ahead of the convex bed means to set up the desired tension in the traveling strip. The latter may be tensed in any suitable manner which occurs to one skilled in the

art. For example, the strip may be pulled past any particular die means or die roller, or pair thereof, under certain tension by power driving strip-transporting means at the various stations, or by drive of the bed wheel itself with suitable drag applied. For example, the die rolls at the various stations may be power driven at successively increased surface speeds at the successive stations. The power driving of the die rollers or other strip driving means at the stations should be such that at each station the strip is pulled from a preceding station with the desired tension created to assure that the strip will be kept snugged down on the convex bed means during the curling operations. For example, in a plural curling station apparatus where curling die rolls are positively driven to set up and maintain the necessary tension in the forwardly traveling strip at any three successive stations the die roll means at the second thereof will be driven at a slightly faster surface speed than the die roll means at the first thereof and the die roll means at the third at a slightly faster surface speed than the die roll means at the second. Thus, tension in the strip at that second station to keep the strip there snugged to the convex bed during the curling operation thereat is created by the pull or draft at that third station and relative drag imposed by the slower surface travel of the die roll means at that first station. In turn the pull or draft at the second station cooperates with drag imposed behind that first station to tense the strip at the latter, and pull or draft imposed beyond that third station cooperates with drag effected by the slower surface travel of the die roll means at that second station to set up the required tension at the third station. For such purpose the shafts 41-41 of the die rolls of the embodiments of the apparatus shown by way of example in the drawings can be mechanically connected to powered driving means in any suitable manner readily apparent to one skilled in the art, such as by suitable conventional trains of gears (not shown). They can be driven at the same rotary speeds with the increased surface speeds at the successive stations attained by decrease in diameter of the die rolls, with the smaller diameter die roll being located at the first station and those at the other stations being progressively larger.

It will thus be seen that the objects set forth above and those made apparent from the preceding description are efficiently attained and, since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. Apparatus for curling longitudinal edges of substantially flat strips of deformable and settable sheet material comprising, in combination, means arranged longitudinally in arcuate outline as viewed from the side as distinguished from any transverse shaping thereof and forming a longitudinally-arched strip-supporting and back-

ing bed means defining a fixed route, longitudinally-arched curved path, means to draft such strip longitudinally over said arcuately arranged arched bed means along the fixed route curved path, means to apply drag to the drafted strip as it is moved along the fixed route curved path to impose thereon some longitudinal tension with support by said bed means, and die means substantially fixedly located at at least one position along one side of the fixed route curved path in the path of forward travel of one edge of the tensed strip into which said edge is to be forwardly moved, said die means being shaped to apply lateral push and lift to that edge as it is moved forward thereinto to curl it back upon the body of the tensed strip as the latter is drafted forward and supported at that position by the backing bed means, and means substantially to prevent lateral shift of said strip on said bed means as said die means applies lateral push to that edge.

2. Apparatus for curling longitudinal edges of substantially flat strips of deformable and settable sheet material having at least certain limited rigidity so as to transmit transversely some push applied laterally to edges thereof comprising, in combination, means arranged longitudinally in arcuate outline as viewed from the side as distinguished from any transverse shaping thereof and forming a longitudinally-arched strip-supporting and backing bed means defining a fixed route, longitudinally-arched curved path, means to draft such strip longitudinally over said arcuately arranged arched bed means along the fixed route curved path, means to apply drag to the drafted strip as it is moved along the fixed route curved path to impose thereon some longitudinal tension with support by said bed means, die means substantially fixedly located at at least one position along one side of the fixed route curved path in the path of forward travel of one edge of the tensed strip into which said edge is to be forwardly moved, said die means being shaped to apply lateral push and lift to that edge as it is moved forward thereinto to curl it back upon the body of the tensed strip as the latter is drafted forward and supported at that position by the backing bed means, and means on the opposite side of the fixed route curved path against which the opposite edge of the tensed strip may abut to resist transverse strip motion during edge curling.

3. Apparatus for curling longitudinal edges of substantially flat strips of deformable and settable sheet material having at least certain limited rigidity so as to transmit transversely some push applied laterally to edges thereof comprising, in combination, means arranged longitudinally in arcuate outline as viewed from the side as distinguished from any transverse shaping thereof and forming a longitudinally-arched strip-supporting and backing bed means defining a fixed route, longitudinally-arched curved path, means to draft such strip longitudinally over said arcuately arranged arched bed means along the fixed route curved path, means to apply drag to the drafted strip as it is moved along the fixed route curved path to impose thereon some longitudinal tension with support by said bed means, die means substantially fixedly located at at least one position along one side of the fixed route curved path in the path of forward travel of one edge of the tensed strip into which said edge is to be forwardly moved, said die means being shaped to apply lateral push and lift to that

edge as it is moved forward thereinto to curl it back upon the body of the tensed strip as the latter is drafted forward and supported at that position by the backing bed means, and other 5 similar die means on the opposite side of the fixed route curved path in the path of forward travel of the opposite edge of the tensed strip also to curl the latter edge back upon the strip body with die means on one side serving as abutment means for die means on the other side to resist transverse strip motion during edge curling.

4. Apparatus for curling longitudinal edges of substantially flat strips of deformable and settable sheet material having at least certain limited rigidity so as to transmit transversely some push applied laterally to edges thereof comprising, in combination, a rotatable endless bed guided in motion along a substantially fixed 15 route convex path provided by a portion of said bed, means to draft such a strip over said bed along the fixed route convex path, means to apply drag to said strip as it is drafted over said bed to impose thereon some longitudinal tension 20 with support by said bed and with bed motion avoiding relative motion between it and the tensed strip, and die means substantially fixedly located at at least one position along one side of the fixed route convex path in the path of forward travel of one edge of the tensed strip into which said edge is to be forwardly moved, said die means being shaped to apply lateral push and lift to that edge as it is moved forward thereinto to curl it back upon the body of the strip 25 as the latter is drafted forward under tension while being supported at that position by the underlying bed means.

5. Apparatus as defined in claim 4 characterized by rotatable wheel-like means the rim of which serves as the endless bed.

6. Apparatus as defined in claim 4 in which said lateral shift-preventing means comprises additional means provided on the opposite side of the fixed route curved path against which the opposite edge of the strip may abut to resist transverse strip motion during edge curling.

7. Apparatus as defined in claim 4 in which there is provided additional similar die means on the opposite side of the fixed route curved path to curl up in like manner the opposite edge of the strip with either die means on one side serving to resist transverse strip motion during edge curling on the opposite side.

8. Apparatus as defined in claim 4 characterized by rotatable wheel-like means the rim of which serves as the endless bed and in which said lateral shift-preventing means comprises additional means provided on the opposite side of the fixed route curved path against which the opposite edge of the strip may abut to resist transverse strip motion during edge curling.

9. Apparatus as defined in claim 4 characterized by rotatable wheel-like means the rim of which serves as the endless bed and in which there is provided additional similar die means on the opposite side of the fixed route curved path to curl up in like manner the opposite edge of the strip with either die means on one side serving to resist transverse strip motion during edge curling on the opposite side.

10. Apparatus as defined in claim 1 in which the bed means in the fixed route curved path portion thereof is provided at that die means position with an outer strip-contacting surface that is slightly V-shaped in a transverse direction to

13

prevent the tensioned strip while being drafted thereover from tending to shift laterally with unequal resistance to lateral push applied at opposite edges thereof.

11. Apparatus as defined in claim 4 in which the bed in the fixed route curved path portion thereof is provided with an outer strip-contacting surface that is slightly trough-shaped to prevent the tensioned strip while being drafted thereover from tending to shift laterally with unequal resistance to lateral push applied at opposite edges thereof. 5

12. Apparatus as defined in claim 4 in which the bed in the fixed route curved path portion thereof is provided with an outer strip-contacting surface that is slightly V-shaped transversely to cause a tensioned strip while being drafted thereover to assume a like V-shape to prevent lateral shifting thereof with unequal resistance to lateral push applied at opposite edges of the strip during curling. 10

13. Apparatus as defined in claim 4 in which there is provided additional similar die means on the opposite side of the fixed route curved path to curl up in like manner the opposite edge of the strip with either die means on one side serving to resist transverse strip motion during edge curling on the opposite side and in which the bed in the curved path portion thereof is provided with an outer strip-contacting surface that is slightly V-shaped transversely to cause a tensioned strip while being drafted thereover to assume a like V-shape to prevent lateral shifting thereof with unequal resistance to lateral push applied at opposite edges of the strip during curling. 20

14. Apparatus as defined in claim 4 characterized by rotatable wheel-like means the rim of which serves as the endless bed with the rim having its outer strip-contacting surface slightly V-shaped transversely to cause a tensioned strip while being drafted thereover to assume a like V-shape to prevent lateral shifting, and in which there is provided additional similar die means on the opposite side of the curved path to curl up in like manner the opposite edge of the strip with either die means on one side serving to resist transverse strip motion during edge curling on the opposite side. 25

15. Apparatus for curling longitudinal edges of substantially flat strips of deformable and settable sheet material having at least certain limited rigidity so as to transmit transversely some push applied laterally to edges thereof comprising, in combination, a rotatable wheel of relatively large diameter mounted for free rotation on a substantially horizontal axis, a rim for said wheel in the form of a circular band substantially coaxial with the axis of said wheel and provided with a radially extending abutment flange on one side thereof, means to draft a continuous strip of the type indicated over said rim at the top portion of said wheel, means to apply drag to the drafted strip to impose tension thereon as it is drafted over said rim, and a plurality of die rollers mounted along the path of the rim at the top portion of said wheel to the side opposite said abutment flange progressively to curl up one edge of the tensioned strip as the opposite edge thereof is abutted against said flange. 30

16. Apparatus as defined in claim 15 in which means are provided to apply liquid material to the outer face of the strip at a station preceding said die rollers. 70

17. Apparatus for curling longitudinal edges of substantially flat strips of deformable and set- 75

14

table sheet material having at least certain limited rigidity so as to transmit transversely some push applied laterally to edges thereof comprising, in combination, a rotatable wheel of relatively large diameter mounted for free rotation, a rim for said wheel in the form of a circular path having its outer strip-contacting surface slightly V-shaped transversely, and a plurality of opposed pairs of die rollers mounted along an arcuate portion of the path of the rim to opposite sides of the plane through the outer rim surface where the latter is of less diameter with the die rollers in each pair in the direction of forward travel of the strip being successively closer together progressively to curl up the opposite edges of the strip as it is drafted forward over the top portion of said wheel. 10

18. Apparatus as defined in claim 17 characterized by mounting of the die rollers radially beyond the strip-contacting surface of said rim with the peripheral edge of the inner end of each die roller contacting the rim surface for rotation of the former by the latter during draft of the strip on said wheel with rotation of the latter. 15

19. Apparatus as defined in claim 17 in which the die rollers are mounted above the rim along a top portion of said wheel with each mounted for rotation about an axis extending outwardly toward the mentioned plane at an angle to the strip-contacting surface of the rim less than ninety degrees (90°) to cause the periphery of the bottom end of each die roller on the inner side thereof nearest the mentioned plane to contact the rim surface for forward friction wheel rotation thereof as said wheel is rotating with forward draft of the strip. 20

20. Apparatus as defined in claim 17 in which the die rollers are mounted above the rim with each mounted for rotation about an axis extending outwardly toward the mentioned plane at an angle to the strip-contacting surface of the rim less than ninety degrees (90°) to cause the periphery of the bottom end of each die roller on the inner side thereof nearest the mentioned plane to contact the rim surface for forward friction wheel rotation thereof as said wheel is rotating with forward draft of the strip, and in which applicator means is provided to apply fluid material to the outer face of the strip at a station preceding said pairs of die rollers. 40

21. A method of curling longitudinal edges of substantially flat strips of deformable and settable sheet material having at least certain limited rigidity so as to transmit transversely some push applied laterally to edges thereof comprising moving such a strip forward under tension longitudinally along a fixed route, longitudinally-arched curved path defined by strip-supporting, longitudinally-arched backing bed means arranged longitudinally in arcuate outline as viewed from the side as distinguished from any transverse shaping thereof, and drawing an edge of said strip during its tensed motion into fixed-position laterally offset curling means to apply lateral push and lift to that edge to curl it up while preventing lateral shift of said strip with the tension therein maintaining the uncurled portion snugly against said bed means at said curling means position. 50

22. A method of curling longitudinal edges of substantially flat strips of deformable and settable sheet material having at least certain limited rigidity so as to transmit transversely some push applied laterally to edges thereof comprising bowing such a strip outward and moving it 60

forward longitudinally along a fixed route, longitudinally-arched curved path, backing said travelling strip by longitudinally-arched means arranged longitudinally in arcuate outline as viewed from the side as distinguished from any transverse shaping of the latter and which defines said longitudinally-arched path, intercepting an edge of said travelling strip with fixed-position pushing and lifting curling means located along said path to apply lateral push and lift to that edge to curl the latter up on itself away from said backing means, restraining at said curling means lateral lift of that portion of the strip which is not being curled, and applying and maintaining tension in said travelling strip at said curling means to restrain lift of its uncurled portion away from said backing means.

23. A method of curling up a longitudinal edge of a substantially flat deformable and settable strip comprising moving said strip longitudinally across convex backing means, applying lateral push and lift away from said backing means to that edge to roll it up off of said backing means progressively during travel of said strip across said backing means with restraint of lateral strip shift, and maintaining said strip under tension during its travel across said backing means with the components of the resulting force applied to said strip as a whole in the direction toward said backing means being greater than components of force in the opposite direction applied to said strip as lift by the rolling operation to maintain the strip as a whole snugged against said backing means during rolling.

24. The method as defined in claim 23 characterized by creation of the tension in said strip by pulling it forward in opposition to forces of drag applied thereto.

25. The method as defined in claim 24 characterized by moving the strip-contacting surface of said backing means forward with travel of said strip to minimize relative motion therebetween.

26. The method as defined in claim 23 characterized by simultaneous progressive rolling up of opposite edges of said travelling tensed strip with lateral strip shift being restrained by the lateral pressure applied on opposite sides thereof during the rolling operations.

27. Apparatus for curling longitudinal edges of substantially flat strips of deformable and settable sheet material having at least certain limited rigidity so as to transmit transversely some push applied laterally to edges thereof; comprising, in combination; relatively fixed position, strip-supporting means arranged longitudinally in arcuate outline as viewed from the side as distinguished from any transverse shaping thereof and forming an elongated, longitudinally-arched,

backing bed means defining a fixed route, longitudinally arched, curved path; means to draft such strip longitudinally over said arcuately arranged, longitudinally arched bed means along the fixed route curved path defined by the latter; means to apply drag to the drafted strip as it is moved along the fixed route curved path defined by said bed means to impose on said strip some longitudinal tension and snug it up to said longitudinally arched bed means for backing support by the latter, the draft and drag means being adapted to apply to the bed-backed portion of said strip as it travels longitudinally across said fixed-position, longitudinally arched, elongated bed means their opposing forces angularly with respect to each other to cause that strip portion to be bowed against said longitudinally arched bed means to the fixed route curved path defined by the latter; and a plurality of successively-arranged pairs of fixed-position die rollers located at successive stations along said fixed route curved path with those of each pair being located on opposite sides of the curved path in the paths of forward travel of the two edges of the tensed strip into which said edges are to be forwardly moved, said die rollers being shaped to apply opposed lateral push and simultaneous lift to those strip edges as the latter are moved forward into said die rollers progressively to curl those edges up toward each other back upon the main body of the tensed strip as the latter is drafted forward and supported at said stations by the backing bed means, the rollers of said pairs being transversely spaced closer together progressively in the direction of travel of such tensed strip to accommodate the progressive narrowing of the strip as its edges are progressively curled up to assure curling action at each of the succeeding stations on partially curled strip edges.
